corporation of Illinois

Application April 27, 1939, Serial No. 270,296

4 Claims. (Cl. 62—178)

This invention relates to the art of refrigeration and has reference to improved methods of and apparatus for heat transfer which are particularly useful in providing different temperature and humidity conditions within different compartments at the same time.

This application is a continuation, in part, of my prior application Serial No. 179,249, filed December 11, 1937, for Method of and apparatus for heat transfer, which in turn is a continuation, in part, of an application filed December 30, 1935, Serial No. 56,625, for Method of and apparatus for heat transfer.

A principal object of the invention is to provide an improvement in the art of refrigeration by means of which refrigeration at different temperatures may be produced simultaneously.

Another object of the invention is to provide a new and improved form of evaporator construction which is adapted to refrigerate simultaneously at different temperatures.

Another object of the invention is to provide a novel and improved refrigerating system including an evaporator which comprises a plurality of separated sections so arranged that a refrigerant body or medium, comprising a plurality of liquid components, or a plurality of different refrigerants having different boiling points is exposed to substantially the same suction pressure in each of the sections in a definite order, as a result of which refrigeration is produced in each of the sections at a temperature different than that of the other sections.

Another object of the invention is to provide in a refrigerating system, an evaporator having one section wherein refrigeration at a low temperature is produced and another section wherein refrigeration at a different temperature is produced.

Another object of the invention is to provide a novel form of heat transfer system wherein there is employed a liquid heat transfer or refrigerating medium which comprises a mixture or solution of at least two refrigerants, said solution or mixture having a different boiling point than either of its components.

Another object of the invention is to provide a refrigerating system which is provided with a two-part evaporator, the liquid refrigerant mixture or solution in each of which part being exposed to substantially the same suction pressure, and the mixture or solution of refrigerants being of such a character that in one part of the evaporator the same boils or evaporates at a lower temperature than at which the mixture or

solution boils in the other part of the evaporator.

Another object of the invention is to provide in a refrigerating system an evaporator which will operate to produce refrigeration at two different temperatures.

Another object of the invention is to provide a new and improved form of refrigerator construction having a plurality of refrigerated zones, each zone having different temperature and relative humidity conditions than those of the other zones.

Another object of the invention is to provide a novel process of refrigeration by means of which refrigeration at a plurality of different temperatures may be produced in a system simultaneously.

Another object of the invention is to provide new and improved forms of refrigerating apparatus which are useful generally in the refrigeration art and independently of the new and improved form of two-temperature refrigeration herein disclosed.

As illustrated in the drawings, my invention is shown as being embodied in a refrigerating system and refrigerator of the so-called domestic type and which comprises in general a heat insulated compartment and a refrigerating system which includes two evaporators, one of the evaporators being arranged within the heat insulated compartment for cooling the air therein and the other of said evaporators being arranged within a second compartment within the heat insulated compartment and shielded from the circulating air therein, one of said evaporators being adapted to produce refrigeration at a different temperature level than that produced by the other of said evaporators and both of said evaporators being of such capacity, with respect to the compartment in which they are arranged, as to produce different temperature and humidity conditions in each of said compartments.

Another object of the invention is to provide a new and improved form of refrigerating system which will operate to produce refrigeration at a plurality of different temperatures simultaneously.

Another object of the invention is to provide a new and improved form of evaporator construction which has one part particularly designed for fast ice freezing and for the low temperature storage of frozen foods and another part which is particularly designed for air cooling and is of such capacity and operated at such a temperature relative to the space to be cooled as to provide more favorable temperature and

humidity conditions within such space, for the storage of foodstuffs.

Another object of the invention is to provide a new and improved form of refrigerating system and refrigerant for use therein, so that said system will operate to produce refrigeration at a plurality of different temperature levels at the same time.

Another object of the invention is to provide a new and improved form of "two-temperature" refrigerating system, which is simpler in construction, more efficient in operation, more dependable in operation, and less expensive to build than two-temperature systems of the type heretofore known to the art.

Another object of the invention is to provide a new and improved form of evaporator construction which is particularly designed for air cooling and which is of such capacity that it may be operated at a higher temperature level than evaporators of the type heretofore known to the art and yet produce lower box temperatures and higher humidity conditions than have been produced by evaporators of the type heretofore used.

Another object of the invention is to provide a new and improved system for ice freezing and air cooling functions, and a new arrangement of the evaporators which perform such functions within a heat insulated compartment.

Other objects and advantages of the invention will be apparent from a consideration of the following specification taken in conjunction with the accompanying drawings of which there are four (4) sheets and wherein:

Fig. 1 is an elevational view of a household refrigerator with parts broken away and illustrating the application of my invention in conjunction therewith;

Fig. 2 is an enlarged front elevational view of the evaporator and the arrangement thereof relative to the space within the heat insulated compartment;

Fig. 3 is a side elevational view of the evaporator shown in Fig. 2;

Fig. 4 is a horizontal section taken in the plane on the line 4—4 of Fig. 3 looking in the direction of the arrows;

Fig. 5 is a top plan view of the evaporator;

Fig. 6 is a vertical sectional view taken in a plane along the line 6—6 of Fig. 5 looking in the direction of the arrows;

Fig. 7 is a horizontal section taken in a plane along the line 7—7 of Fig. 6 looking in the direction of the arrows;

Fig. 8 is a horizontal section taken in a plane along the line 8—8 of Fig. 6 looking in the direction of the arrows;

Fig. 9 is a vertical section taken on a plane along the line 9—9 of Fig. 7 looking in the direction of the arrows; and

Fig. 10 is a perspective view of the two evaporators with parts being broken away to illustrate the refrigerant circulation through such evaporators.

Referring now to Fig. 1, there is shown a heat insulated refrigerator of the household type and constructed so as to provide therein a heat insulated compartment or relatively high temperature cooling zone 20, the opening to which is closed by door 22, and an apparatus compartment 24. The refrigerator also includes, as illustrated, a refrigerating system of the compressor-condenser-expander type and which system includes a compressor, indicated generally at 26, and a

condenser 28 arranged within the apparatus compartment 24 and operatively connected to a pair of evaporators 30 and 32 arranged within the compartment 20. The discharge side of the

5 compressor is connected to one end of the condenser and the other end of the condenser is connected to the evaporator 30 so as to supply liquid refrigerant thereto under the control of a suitable refrigerant expansion control; the evaporator 30 10 is connected in series with the evaporator 32 and the suction side of the compressor is connected to the vapor space of the evaporator 32. The compressor 26 may be driven by an electric motor arranged within the sealed casing in which 15 the compressor 26 is arranged, and current will be supplied to the motor through an electric conduit 34 adapted for attachment to an ordinary electric receptacle. The supply of current to the motor is under the control of a suitable thermostatic switch as will be explained hereinafter.

The evaporator 30, it will be observed, is arranged in the upper left-hand corner of the compartment 20, and the evaporator 32 is arranged alongside of the evaporator 30. The evaporator 30, as will be more fully explained hereinafter, comprises a low temperature or ice freezing evaporator which is constructed and arranged for operating at relatively low temperatures, for example, from 0 to 10° F., and is shielded from the 25 circulating air within the compartment 20, to define a relatively low temperature or freezing zone. The evaporator 32 is particularly designed for air cooling and is constructed and arranged to operate at a temperature level of from 19 to 29° 30 F., the area of the evaporator 32 exposed to the circulating air within the compartment 20 being sufficient so as to produce a temperature within the compartment preferably of from 35 to 40° F. during the normal operation of the system.

40 Referring now to Fig. 10 wherein the refrigerant circulation of the two evaporators is illustrated, liquid refrigerant from the condenser and under the control of a suitable refrigerant expansion control is supplied to the low temperature evaporator 30 through liquid line 36 and vaporous refrigerant is returned to the intake side of the compressor from the evaporators through the suction line 38. The evaporator 30, as illustrated, consists of a plurality of refrigerated plates or shelves 42, 44 and 46, each shelf comprising a flat metallic plate 48 having a coiled refrigerant duct 50 in good thermal conductivity with the underside thereof. Liquid refrigerant is supplied to the coils or ducts 50 of the shelves 42, 44 and 46, in series, in the order named, the refrigerant flow through the ducts 50 being in the direction indicated by the arrows. From the upper shelf 46 of the low temperature freezer 30 refrigerant is supplied through conduit 52 to a distributing header 54 of the box cooling evaporator 32. The box cooling evaporator comprises a finned plate evaporator exposed to the air within the provision compartment 20 and the details of the construction of which will be described hereinafter. The suction line 38 is connected to an upper header 56 of the evaporator 32 for returning vaporous refrigerant and lubricant entrained therewith to the intake side of the compressor.

45 The evaporators 30 and 32, it will be observed, are connected in series and due to the fact that there are no restrictions or pressure regulating means between the two evaporators, refrigerant in the coils or ducts of both of the evaporators 50 will be exposed to substantially the same suction

pressure. Under these conditions, if a single refrigerant such as sulphur dioxide (SO_2) or any one of the "F" refrigerants now being marketed under the name "Freon" is used in the refrigerating system, as could be done, the evaporation of refrigerant would take place in both of the evaporators and in all parts thereof at substantially the same temperature level. While a single refrigerant could be used in the arrangement illustrated, the present invention contemplates the operation of the evaporator 30 at a lower temperature level than the evaporator 32. One example of a means which may be employed to obtain the production of refrigeration at different temperature levels in the evaporators 30 and 32 is the use in the system of a refrigerant which consists of a solution or mixture of two or more refrigerant components such as, for example, a refrigerant consisting of 80 to 90%, by weight, of (F-21) dichloromonofluoromethane (CHCl_2F) and 10 to 20%, by weight, of (F-12) dichlorodifluoromethane (CCl_2F_2). Other examples of refrigerants comprising a mixture or solution of two or more refrigerant components suitable for use in the system herein illustrated and capable of effecting the operation of the evaporators at different temperature levels are:

Sulphur dioxide (SO_2) and trichloromonofluoromethane (CCl_3F) (F-11)
 Sulphur dioxide (SO_2) and dichloromonofluoromethane (CHCl_2F) (F-21)
 Sulphur dioxide (SO_2) and dichlorotetrafluoroethane ($\text{C}_2\text{Cl}_2\text{F}_4$) (F-114)
 Methyl chloride (CH_3Cl) and dichlorodifluoromethane (CCl_2F_2) (F-12)
 Methyl chloride (CH_3Cl) and trichloromonofluoromethane (CCl_3F) (F-11)
 Methyl chloride (CH_3Cl) and dichlorotetrafluoroethane ($\text{C}_2\text{Cl}_2\text{F}_4$) (F-114)
 Methyl chloride (CH_3Cl) and dichloromonofluoromethane (CHCl_2F) (F-21)
 Dichlorodifluoromethane (CCl_2F_2) (F-12) and trichloromonofluoromethane (CCl_3F) (F-11)
 Dichlorodifluoromethane (CCl_2F_2) (F-12) and dichlorotetrafluoroethane ($\text{C}_2\text{Cl}_2\text{F}_4$) (F-114)

In addition to the foregoing mixtures or solutions, other mixtures or solutions of two or more refrigerant components may be used. For further examples of mixtures reference may be had to my prior copending application Serial No. 179,249, filed December 11, 1937, for "Method of and apparatus for heat transfer."

Dichlorodifluoromethane (CCl_2F_2), trichloromonofluoromethane (CCl_3F), dichlorotetrafluoroethane ($\text{C}_2\text{Cl}_2\text{F}_4$) and dichloromonofluoromethane (CHCl_2F) chemically may be classified as fluorine derivatives of an aliphatic halogen compound, and are commercially referred to as F-12, F-11, F-114 and F-21, respectively.

Theoretically, if a mixture of approximately 20% of F-12 in F-21 at 10 lbs. absolute pressure is supplied to the low temperature evaporator 30, a shelf temperature of 10° F. ought to be produced. In the low temperature evaporator 30, the F-12 will evaporate from the mixture or solution in a much larger concentration than 20% and will thereby reduce the concentration of F-12. The almost pure F-21 will then feed over through conduit 52 to the higher temperature evaporator 32 and at 10 lbs. absolute will vaporize at approximately 25° F.

In actual performance, however, the evaporator, as illustrated, with a 20% concentration of F-12 entering the low temperature evaporator 30

will not produce a temperature of 10° F. at 10 lbs. absolute due to the fact that, first, the liquid refrigerant mixture supplied through the liquid line 36 must be reduced in temperature to the boiling temperature and this reduction in temperature is obtained by vaporizing a high concentration of F-12 so that the final concentration is something less than 20%. Second, in cooling the shelves, or low temperature evaporator 30, more heat is added to the refrigerant mixture and the final temperature obtained is an average between the boiling point of the initial concentration and the concentration leaving the shelves. From actual experience it appears possible to obtain approximately one half of the theoretical spread.

The temperature spread between the evaporators 30 and 32, however, will vary materially with the heat load in the compartment 20 due to the fact that the available refrigeration per pound of mixture is constant, and since more refrigerant or mixture is circulated at higher loads, more refrigeration is available at the lower temperature level.

A greater temperature spread between the evaporators 30 and 32 may be obtained by using a larger concentration of F-12, for example.

It appears desirable to operate the low temperature evaporator 30 at a temperature level of approximately 10° F. and the air cooling section at a temperature of approximately 19° F.

In a system of this type, the addition of F-12 tends to increase the condenser head pressure and thereby increase the power input to the compressor. However, it has been found that in a well built compressor with low friction losses, the increase in head pressure increases the power input very slightly and there is a tendency for an overall gain in power consumption per day because the suction pressure increases slightly and both evaporators are somewhat more efficient, due to the improved ebullition resulting from the increased quantity of gas flowing through them, and, also, due to the extended surface provided by the fins on the air cooling evaporator.

The mixture just described of F-12 and F-21 may be classified by what is commonly termed a normal boiling point mixture. In this mixture the boiling point is always between the boiling point of the pure constituents. In operation, a system such as the one illustrated is charged with a quantity of refrigerant which is a mixture or solution of a plurality of refrigerant components such as a 20% solution of F-12 in F-21. Where the evaporator comprises a plurality of sections or parts, as illustrated in the drawings, the refrigerant medium will operate to produce refrigeration at a lower temperature in the evaporator 30 than in the evaporator 32 because the refrigerant solution or mixture in the evaporator 30 will contain a different percentage of the components of the refrigerant than the solution or mixture which vaporizes in the evaporator 32. As the solution in the evaporator 30 will boil at a lower temperature than the solution in the evaporator 32, there will be a temperature differential or spread between the evaporators 30 and 32.

The refrigerant medium in circulating through the system is discharged from the compressor into the condenser where condensation of all of the vaporous refrigerant takes place, and is thence conducted, under the control of a refrigerant expansion control, to the low temperature

evaporator 30 wherein a part of the solution or mixture will vaporize and the remainder of the mixture or solution, together with the gas generated in the evaporator 30, will be conducted by conduit 52 into the evaporator 32. In the low temperature evaporator 30, the vapor coming off of the refrigerant mixture will contain a greater percentage of the refrigerant component having the high volatility or lower boiling point, with the result that the residual refrigerant which is delivered into the evaporator 32 has a lower percentage of the higher volatile component in it than is present in the mixture or solution in the evaporator 30. The liquid refrigerant discharged into evaporator 32 has a higher boiling point than the boiling point of the solution in the evaporator 30, and, hence, will boil at a higher temperature. Therefore, it is apparent that refrigeration at a lower temperature level will be produced in the evaporator 30 than in the evaporator 32.

The vaporous refrigerant from both of the evaporators 30 and 32 will collect in the upper part of the header 54 from whence suction line 38 conducts such refrigerant vapor together with whatever lubricant may be entrained therein to the intake side of the compressor. The average composition of the gas passing through the suction line should always be the same as the average composition of the liquid entering evaporator 30 through liquid line 36.

The details of construction of the two evaporators are illustrated in Figs. 2 to 9, inclusive, and to which figures reference will now be made. The inner wall or lining of the compartment 20 may be provided by a sheet metal tank 60 terminating at its front in a flat face 62 upon which a breaker strip or throat lining 64 is seated. The breaker strip 64 extends continuously around the door opening and is adapted to cooperate with a gasket, carried by the door 22, for sealing the access opening to the compartment 20 when the door 22 is in closed position. An L-shaped partition 66 extending from the back wall of the compartment 20 to the front thereof cooperates with the lining 60 at the upper left-hand corner of the compartment 20 to define a low temperature compartment 21 in which the evaporator 30 is disposed. The edges of the partition 66 may be provided with flanges 68 which seat against the flat surface of the tank 60 and are provided with bolt holes through which, and aligned holes in the tank 60, bolts 70 extend for securing the partition 66 in place. Preferably a gasket 72 is arranged between the flanges 68 and the wall of the tank 60 so as to provide a thermal break therebetween, and also so as to effectively seal the compartment 21 around the edges thereof. A continuous rectangular metallic frame 74, covered by a continuous rubber gasket 76, is fitted at the front of the partition 66, and between the same and the opposite walls of the tank 60 defining the compartment 21 (as illustrated in Fig. 4) to define an access opening to the compartment 21. The gasket 76 is arranged between the frame 74 and the partition 66 at the bottom and the right-hand side of the compartment 21 and between the frame 74, and the tank lining 60 at the top and left-hand side of the compartment 21 and, as illustrated in Fig. 4, thereby sealing the frame 74 to the walls of the compartment 21. The gasket 76 includes a continuous hollow bead 78 which cooperates with the edges of a dished door member 80 to seal the interior of the compartment 21 from the

compartment 28 when the door 80 is in closed position, as illustrated in Fig. 4. The door 80 may be pivotally hung on hinge means 82 suitably carried by the partition 66. A spring clip 84, carried by the frame 74, may be provided for engaging the door 80 to hold the same in closed position. Handle 86 carried by the door 80 may be provided for opening and closing the door. At the front and rear edges thereof, and 10 on the left-hand side, as shown in Fig. 2, the shelves 42, 44 and 46 of the low temperature evaporator 30 may be bolted to vertical straps 90 and these straps in turn are bolted, or otherwise suitably secured, such as by bolts 92, to the tank lining 60 for supporting such shelves. The frame 74 also is bolted by bolts 94 to the tank lining 60 at the left-hand side and top thereof, and to the partition 66 at the right-hand side and bottom, for securing the same in place. Preferably, the straps 90 are spaced from the tank lining by gaskets 96 held in place by bolts 92. The right-hand side of the shelves 42, 44 and 46, at the front and rear thereof, are connected to the partition 66 so as to be supported thereby and through insulating links 98. A false bottom 100 may be provided inside of the compartment 21 and supported upon the horizontal portion of the partition 66 so as to provide an additional shelf. The shelves 42, 44, 46 and 100 provide surfaces adapted to support liquid holding trays, such as ice trays 102.

The shelf 104 may extend across the compartment 20 immediately below the evaporators 30 and 32 and be provided with a part having spaced guide rails 106 adapted for slidably supporting a pan 108, the top of the pan being open and spaced slightly below the bottom of the partition 66, so that such partition 66 in effect forms a cover for the pan and permits a restricted circulation of air between the interior of the pan and the compartment 20. A water collecting bottle 110 may be suitably supported behind the pan 108 and have an opening immediately below a drain port 112 formed in the partition 66, the bottle 110 serving to collect the drip from the inside of the compartment 21 during the "defrosting" thereof.

The air cooling evaporator 32, as illustrated, comprises a vertical metallic plate having refrigerant ducts or passageways 114 provided internally thereof, and having fins 116 secured thereto, in good thermal conductivity with the refrigerant in the ducts 114. The evaporator 32 may consist of a pair of metallic plates 118 of suitable configuration and which are stamped, or otherwise formed, previous to the assembly thereof, with grooves or channels which after the assembly of the plates 118, form the ducts 114. The plates 118 also are formed prior to assembly so as to provide the liquid distributing header 55 and the upper header 54. Every pair of the ducts 114 are cross connected at the bottom and communicate with the headers 55 and at the upper ends thereof open into the bottom of the upper header 54. The conduit 52 extends through header 55 and is provided with a series of openings 120 which discharge liquid and vaporous refrigerant upwardly in every other duct 114 so as to expedite the circulation of liquid through the ducts 114. The plates 118 may be secured together, such as by welding, and, likewise, the fins are preferably welded or soldered to the sides of the evaporator and in good thermal conductivity with the walls of ducts 114, as illustrated in Fig. 8. The evaporator 32, as

will be apparent from Figs. 5 and 6, is spaced from the partition 66 so as to permit the circulation of air in the compartment 20 in heat exchange relationship with both sides of the evaporator 32. A shallow tray 124, carried by the shelf 104, is arranged below the evaporator 32 for collecting the drip therefrom and is provided with a spout 126 for discharging such drip into the receptacle 110 through the open top thereof. The evaporator 32 preferably is supported from the walls of the tank 60 by means of a plurality of brackets 128 bolted thereto. The partition 66 may be formed to provide a shield 130 which is arranged in front of the evaporator 32, and this shield may be used for supporting a cold control or thermostatic switch 132 having manual control 134, by means of which the temperature setting of the switch may be changed, and as well as to provide a cut-off for the current supply to the motor compressor unit. The cold control consists of a switch which is operated by thermostatic element 136 clamped to one side of the air cooling evaporator 32. The switch 132 opens and closes the motor circuit so as to operate the compressor in such a way as to maintain the temperature of the evaporator 32 and the compartment 20 within certain predetermined limits. The openings through which the conduits 36 and 52 extend through the partition 66, preferably are sealed by gaskets.

In the operation of the evaporators 30 and 32, and with the system charged with one of the binary refrigerants referred to, vaporization of liquid refrigerant will take place in the coils of the shelves 42, 44 and 46 producing refrigeration at a suitable low temperature level. The gas evolved in the coils of the evaporator 30, together with the liquid refrigerant is thence conducted by conduit 52 and distributed by means of header 55 to the ducts of evaporator 32. Upon the absorption of sufficient heat refrigerant will vaporize in the ducts, collect in the header 54 and thence be returned by the suction line to the intake side of the compressor where all of the refrigerant vapor is compressed and subsequently condensed in the condenser. As the liquid refrigerant delivered to the evaporator 32 has a reduced amount of the higher volatile component, the temperature at which refrigerant will vaporize in the evaporator 32 is higher than that at which evaporation is effected in the evaporator 30 and, hence, evaporator 32 will operate at a higher temperature level. The fins 116 provide an extended heat exchange surface for the evaporator 32, and, due to the fact that air passes in heat exchange relationship with both sides of the evaporator 32, the temperature of the compartment 20 may be maintained lower, but at a higher relative humidity than is now possible in evaporators now generally being used. While I have shown one particular system of obtaining different temperatures in the evaporators 30 and 32, it is of course contemplated that other systems might be used in connection with the evaporators 30 and 32 so as to maintain the operation thereof at different temperature levels.

While the invention has been described with

some detail, it is to be understood that the description is for the purpose of illustration only and is not definitive of the limits of the inventive idea. The right is reserved to make such changes in the details of construction and arrangement of parts as will fall within the purview of the attached claims.

I claim:

1. The method of producing refrigeration which comprises forming a liquid solution of (CCl_2F_2) and $(C_2Cl_2F_4)$, evaporating liquid from said solution to produce refrigeration at one temperature, transferring liquid from said solution to form a body of refrigerant at another point having a boiling point different than that of said solution, evaporating refrigerant from said body of refrigerant to produce refrigeration at a temperature different than that produced by evaporating refrigerant from said solution, condensing the refrigerant vapor and returning the same in liquid form to said solution.

2. The method of producing refrigeration which comprises forming a liquid solution of (CCl_2F_2) and $(CHCl_2F)$, partially evaporating said solution to produce refrigeration at a first temperature, transferring the resulting liquid and vapor to form a body of refrigerant at another point having a boiling point different than that of said solution, evaporating refrigerant from said body of refrigerant to produce refrigeration at a temperature different than that produced by evaporating refrigerant from said solution, condensing the refrigerant vapor and returning the same in liquid form to said solution.

3. The method of producing refrigeration which comprises forming a liquid solution of (CCl_2F_2) and (CCl_3F) , evaporating liquid from said solution to produce refrigeration at one temperature, transferring liquid from said solution to form a body of refrigerant at another point having a boiling point different than that of said solution, evaporating refrigerant from said body of refrigerant to produce refrigeration at a temperature different than that produced by evaporating refrigerant from said solution, condensing the refrigerant vapor and returning the same in liquid form to said solution.

4. The method of producing refrigeration which comprises forming a refrigerant medium by mixing together polyhalogen substituted lower aliphatic hydrocarbons in which at least one of the substituted halogen atoms is fluorine, said hydrocarbons which are placed together having different boiling points and retaining said different boiling characteristics, evaporating liquid from said solution to produce refrigeration at one temperature, transferring liquid from said solution to form a body of refrigerant at another point having a boiling point different than that of said solution, evaporating refrigerant from said body of refrigerant to produce refrigeration at a temperature different than that produced by evaporating refrigerant from said solution, condensing the refrigerant vapor and returning the same in liquid form to said solution.

EARL F. HUBACKER.
